MULTIVIBRATOR CIRCUIT

William A. Miller, Port Jefferson, N. Y., assignor
to Radio Corporation of America, a corporation
of Delaware

Application May 25, 1950, Serial No. 164,077

6 Claims. (Cl. 250—36)

1

This invention relates to oscillators. More particularly the present invention is an improvement in relaxation oscillators of the type known as multivibrators.

In many applications of multivibrators in sweep circuits or as pulsers, it is desirable that the output voltage or pulses from the multivibrator be clamped or have one extremity of the waveform always return to the same reference potential. D. C. restorers or clamping circuits are employed to perform this function. Furthermore, much, additional, complex circuitry is required in the event it is desired to make the reference potential, to which a waveform is clamped, a variable one. In a copending application for an "Electronic Locking Circuit," Serial No. 164,078, filed May 25, 1950, there is described and claimed a trigger circuit which provides an output which is automatically clamped to a reference potential.

It is an object of the present invention to provide an improved relaxation oscillator having an output which is automatically clamped to a reference potential.

It is another object of the present invention to provide an improved relaxation oscillator having an output which is automatically clamped to a reference potential which is adjustable.

It is still another object of the present invention to provide an improved relaxation oscillator having an output which eliminates the requirement for clamping circuits.

These and further objects of the present invention are achieved by providing a two-tube multivibrator having cross-connected grids and anodes wherein a first one of the tubes has its anode connected to the B+ power supply through a load resistor and its cathode and grid to ground potential and a second one of the tubes has its anode connected to ground potential through a load resistor and its cathode and grid to a negative bias source. This provides, at the anode which is coupled to ground, an output which varies between ground potential and a potential considerably negative to ground. The potential (nearness to ground) to which the output is clamped may be controlled, in some degree, by using a potentiometer to supply suitable potential to the anode of the second tube.

The novel features of the invention as well as the invention itself, both as to its organization and method of operation, will best be understood from the following description, when read in connection with the accompanying drawings, in which

Figure 1 is a circuit diagram of an embodiment of the invention,

2

Figure 2 is a graphical representation of the wave-shapes of the output available from the circuit shown in Figure 1.

Figure 3 is a circuit diagram of a modification of the embodiment of the invention shown in Figure 1, and

Figure 4 is a graphical representation of the wave-shapes of the output available from one of the tube anodes in the circuit shown in Figure 3.

Referring now to Figure 1, a first electron discharge tube 10 has an anode 12 connected to the grid 24 of a second electron discharge tube 20 through a condenser 18. The grid 14 of the first electron discharge tube 10 is connected to the anode 22 of the second tube 20 through a condenser 28. A grid leak resistor 30 is connected between the cathode 16 and grid 14 of the first tube 10. Another grid leak resistor 32 is connected between cathode 26 and grid 24 of the second tube 20.

A source of operating potential 34 is provided having a positive terminal 36 which is positive with reference to ground or a point of reference potential 38, and a negative terminal 40 which is negative with reference to ground 38. A load resistor 42 is connected between the anode 12 of the first tube and the positive terminal 36. The cathode 16 of the first tube is connected to the point of reference potential 38. A load resistor 44 is connected between the anode of the second tube and the point of reference potential 38. The cathode 26 of the second tube is connected to the negative terminal 40.

The operation of the circuit is typically that of a free-running multivibrator. Current conduction is transferred from one tube to the other alternately. The frequency of the transfer, as of the oscillation, is principally determined by the values of the coupling condensers and grid leak resistors, and to a lesser extent by the values of the anode load resistors and the value of the source of operating potential. An explanation of the operation of a multivibrator may be found in "Theory and Applications of Electron Tubes" by Reich, pages 362 to 365, published by McGraw-Hill Book Company.

In the circuit shown in Figure 1, however, in view of the fact that the anode of the second tube 20 is coupled to ground 38, an output taken from the anode when the tube is not conducting is at ground potential. Likewise, an output taken from the anode when it is conducting is negative with respect to ground potential. Referring to Figure 2, the waveshape of the voltage output at the anode 12 of the first tube 10 may be seen as being substantially rectangular and above ground potential. The waveshape of

the voltage output at the anode 22 of the second tube 20 is also substantially rectangular and varies from ground potential, when the tube is not conducting, to a negative value, when the tube is conducting. The amount that the second tube anode will go negative depends upon the amount of current drawn by the tube and the value of the load resistor 44. Therefore, the output from the anode of the second tube is clamped to ground or reference potential. In view of the connection to ground potential, the anode 22 of the second tube 20 may be connected directly to succeeding apparatus without the usual coupling condenser being required to block out anode D. C. potential. No D. C. restoration or clamping is required for an output taken from the anode of the second tube.

Figure 3 is a circuit diagram of a modification of Figure 1. Similar functioning parts of Figure 3 are identified by similar reference numerals. The modification consists of a potentiometer 46 having its fixed resistance 48 connected across the power supply 34 in a manner to include values of potential which are positive referred to the point of reference potential and negative referred to the point of reference potential. This may be done by tapping the source, as shown, using supplementary dropping resistors, or in any other manner which is known to the art. The arm of the potentiometer 50, which is in slidable contact with its fixed resistance, is connected to the anode load resistor 44 of the second tube 20. A condenser 52 is connected between the potentiometer slidable arm 50 and the point of reference potential 38 in order to maintain a constant A. C. load on the second tube.

Movement of the potentiometer slidable arm 50 permits application of potentials from a positive value through zero to a negative value. The effect of these variations on the output from the second tube anode is shown in Figure 4. Pulse A represents a typical output pulse when the slider arm 50 is at the ground potential point. Pulse B represents a typical output pulse when the slider arm applies a voltage which is below ground and pulse C is representative of a typical output pulse when the slider arm applies a voltage above ground. The range over which this variation may be carried out is determined mainly by the amount of voltage swing of the anode 12 of the first tube 10. Thus the reference or clamping level of the output at the second tube anode may be controlled as desired by adjusting the potentiometer. Although the subject multivibrator is described using triodes, multigrid tubes are equally effective.

From the foregoing description it will be readily apparent that there has been provided an improved relaxation oscillator of the multivibrator type having an output which is automatically clamped to a reference potential which may be varied as desired. Although a single embodiment and modification of the present invention has been shown and described it should be apparent that many changes may be made in the particular embodiment herein disclosed, and that many other embodiments are possible, all within the spirit and scope of the present invention. It is desired, therefore, that the foregoing description shall be taken as illustrative and not as limiting.

What is claimed is:

1. A relaxation oscillator comprising first and second electron discharge tubes each having

anode, cathode and grid electrodes, the grid of said first tube being coupled to the anode of said second tube, the grid of said second tube being coupled to the anode of said first tube, a grid leak resistor for each of said tubes connected between the grid and cathode of each tube, a first anode load impedance having one end connected to the anode of said first tube, a second anode load impedance having one end connected to the anode of said second tube, a point of reference potential, said first tube cathode being connected to said point of reference potential, means to apply a potential which is positive with respect to said reference potential point to the other end of said first anode load impedance, means to apply a potential which is negative with respect to said reference potential point to said second tube cathode, means to apply a potential which is positive with respect to said reference potential point to the other end of said second anode load impedance, and means to vary as desired the value of said potential from values above to values below said reference potential point.

2. A relaxation oscillator circuit comprising first and second electron discharge tubes each having anode, cathode and grid electrodes, the grid of said first tube being coupled to the anode of said second tube, the grid of said second tube being coupled to the anode of said first tube, a grid leak resistor for each of said tubes connected between the grid and cathode of each tube, a first anode load impedance having one end connected to said first tube anode, a second anode load impedance having one end connected to said second tube anode, a point of fixed potential, the other end of said second anode load impedance and said first tube cathode being connected to said point of fixed potential, means to apply a potential which is positive with respect to said point of fixed potential to said other end of said first anode load impedance, and means to apply a potential which is negative with respect to said point of fixed potential to said cathode of said second tube.

3. A relaxation oscillator circuit comprising first and second electron discharge tubes each having anode, cathode and grid electrodes, the grid of said first tube being coupled to the anode of said second tube, the grid of said second tube being coupled to the anode of said first tube, a grid leak resistor for each of said tubes connected between the grid and cathode of each tube, a first anode load impedance having one end connected to the anode of said first tube, a second anode load impedance having one end connected to the anode of said second tube, a point of reference potential, said first tube cathode being connected to said point of reference potential, means to apply a potential which is positive with respect to said reference potential point to the other end of said first anode load impedance, means to apply a potential which is negative with respect to said reference potential point to said second tube cathode, a potentiometer including a fixed impedance and an arm slidably in contact with said impedance, said slidable arm being connected to the other end of said second anode load impedance, means to apply a potential which is positive with respect to said reference potential point to one end of said potentiometer fixed impedance, and means to apply a potential which is negative with respect to said reference potential point to the other end of said potentiometer fixed impedance.

4. A relaxation oscillator circuit as recited in claim 3 having in addition a condenser connected

between said potentiometer slidable arm and said point of fixed potential.

5. A relaxation oscillator comprising first and second electron discharge tubes, each tube having an anode, cathode and grid electrode, each tube having a separate grid leak resistor connected between said tube grid and cathode and each tube having a separate load resistor with one end connected to said tube anode, the grid of said first tube being capacitively coupled to the anode of said second tube, the grid of said second tube being capacitively coupled to the anode of said first tube, and a source of operating potential, said source including a point of reference potential, a positive terminal which is more positive than said point of reference potential and a negative terminal which is more negative than said point of reference potential, the other end of said load resistor of said first tube being connected to said positive terminal, said first tube cathode and the other end of said load resistor of said second tube being connected to said point of reference potential, and said second tube cathode being connected to said negative terminal.

6. A relaxation oscillator comprising first and second electron discharge tubes, each tube having an anode, cathode and grid electrode, each tube having a separate grid leak resistor connected between said tube grid and cathode and each tube having a separate load resistor with one end connected to said tube anode, the grid of said first tube being capacitively coupled to the anode of said second tube, the grid of said second tube

being capacitively coupled to the anode of said first tube, and a source of direct current potential, said source including a point of reference potential, a positive terminal which is more positive than said point of reference potential and a negative terminal which is more negative than said point of reference potential, the other end of said load resistor of said first tube being connected to said positive terminal, said first tube cathode being connected to said point of reference potential and said second tube cathode being connected to said negative terminal, a potentiometer including a fixed resistance and an arm slidably in contact with said fixed resistance, 10 means to couple said potentiometer fixed resistance between said positive and negative terminals to provide a range of potentials along said fixed resistance including said reference potential, the other end of said second tube load resistor being connected to said potentiometer slid- 15 able arm and a condenser connected between said second tube load resistor other end and said point of reference potential.
